UNITED STATES PATENT OFFICE.

MAXIMILIAN W. THAETE, OF DENVER, COLORADO, ASSIGNOR OF ONE-HALF TO MILLIE J. THAETE, OF DENVER, COLORADO.

VALVE-SEAT REAMER.

Application filed April 19, 1926. Serial No. 103,026.

My invention relates to reamers for reaming poppet-valve seats, and more particularly to reamers which are adapted to be operated by either the unskilled person or the skilled mechanic with the same degree of success.

It is a well established fact that in order to have the valve seat properly reamed, the valve seats must be of a uniform size. In order to attain such uniformity in size throughout, the use of reamers as now proposed it is required that the reamers be rotated the same number of revolutions in all of the valve seats utilizing the same or substantially the same pressure in each instance. Furthermore, reamers now in use are open to the objection in that they can only be retained in an upright or vertical position by the skill of the mechanic using such reamers and if not retained in such position the valve seat will be cut in ragged or wavy manner. Also the reamers commonly used necessitate the changing of cutters for each change of degree in the valve seat, and the cutters must be changed to ream the top of the block and the port.

Accordingly, an object of my invention is to provide a reamer that will uniformly ream valve seats irrespective of the number of revolutions of the reamer or the pressure applied, thus enabling the use of such reamers by unskilled labor. A poppet valve by use will widen its seat, and it is an object of my invention to provide a reamer that will narrow the valve seat to its proper dimensions in one operation. In order to do this, it is necessary to cut the valve seat, the top of the block and the valve port simultaneously. Formerly, three operations were required.

Another object of my invention is to provide a reamer that will be retained in an upright position while in operation.

A still further object of my invention is to provide a reamer which will cut a narrow or wider seat without necessitating the change in the cutters and will not cut in a ragged or wavy manner.

Other objects of my invention reside in the details of construction as will fully appear in the course of the description hereinafter set forth.

An embodiment of the invention has been illustrated in the accompanying drawings, in which like reference characters designate corresponding parts throughout the several views, and in which,

Figure 1, shows an elevation of my improved reamer;

Figure 2, a vertical section through the cutter and pilot stem, showing the reamer tool partly lifted out of the valve port and the respective angles comprising the valve seat cut by the tool, the stem of the tool being of a one piece construction;

Figure 3, a view showing the cutter, shims, and nut in their respective relations but disassembled;

Figure 4, a modification showing the pilot stem as being removable;

Figure 5, another modification, the stem having a sloping shoulder to engage the cutters;

Figure 6, shows the plug which is used inside the pilot stem of my reamer; and

Figure 7, a modification showing a different manner of mounting the cutters.

Referring further to the drawings, the reamer consists of a shaft 5 having an integral nut 6 at the head thereof and an opening 14. The former is for the application of a wrench, the latter for the insertion of a handle to rotate the tool. The shaft tapers down to a pilot stem 7 at the other end thereof. The shank of the shaft carries screw threads 8 and spaced therefrom is an abutting member or shoulder 9. Serrated cutters 10, 11, and 12 are firmly held on the shank between the shoulder and a nut 13 on the screw threads. These cutters carry teeth which project beyond the side or sides of the cutters and interlock with the teeth of the adjacent cutter, thus forcing all of the cutters to rotate simultaneously with the tool. The teeth are arranged in staggered formation around the tool, which allows the tool to engage the work in numerous places thereby preventing the tool from "chattering" or reaming the valve seat in a wavy manner.

Shims 15 may be used to space the cutters if desired. The tool illustrated is so constructed that if no shims are used, the cutter 11 will not touch the work, and only

the cutters 10 and 12 will ream. As shims are added, cutter 11 is brought forth, and the width of the seat increases.

As drawn, the cutters, 10, 11 and 12 are disposed at angles of 30°, 45° and 75°, respectively, from the horizontal. Therefore the valve seat 22 cut by the tool illustrated would be 45°, the port 24 would be cut at an angle of 75°, and the top of the block 20 cut at an angle of 30°, as graphically shown at 22, 23, and 21 in Figure 2. By changing cutters any angle or angles may be reamed.

The purpose of cutting the port is to provide for the facile escape or entrance of gases or air to or from the port 24, and also to avoid sharp corners, which might interfere with the operation of the valve. Moreover, cutter 12 acts as a guide for cutter 11. The function of cutter 10 is to prevent cutter 11 from reaming a wider seat than is desired, and also to assist in the facile passage of gases to and from the port. Thus it is that irrespective of the amount of pressure applied or the number of times the tool is rotated, the seat cut by cutter 11 will be uniform and no larger than desired, which, as stated, is regulated by the number of shims. Cutter 10 likewise prevents the mechanic from cutting a pocket for the valve seat, which would shut off the passage of gases or air. Any one or more of the cutters may be used by replacing each cutter with a spacer or sleeve. The cutters are removed by unscrewing the nut 13 and pulling the nut and cutters off over the pilot stem 7.

The pilot stem 7 which is of hollow construction, having tapered interior walls, is slit longitudinally as at 16 to within a short distance of the lower end, and is internally screw threaded as at 17 at the lower extremity. A plug 18 is carried in the hollow portion of the pilot stem. The plug carries a screw-threaded, slotted head 19 to engage the threads 17 of the pilot stem, and to provide means for the application of a screw driver.

The sides of the plug engage the interior walls of the pilot stem and as the plug is pushed into the hollow portion of the valve stem by means of the screw-threaded head, the slit sides of the stem are distended. The distension occurs at its greatest degree at the center and gradually recedes toward the ends of the slits.

Thus when the tool with the sides of the pilot stem distended, is pushed down into the valve stem guide 25, the stem frictionally engages the walls thereof, and prevents sideways movement of the tool while the reaming is being done, since the distension occurs practically the full length of the stem. Moreover, the cutter 12 acts as a guide and keeps the cutter 11 in alinement so that the valve seat will be properly reamed.

As stated, it has been necessary in the past

to have skilled labor to place the reamer in position and to operate it for the valve seat must be reamed at the right place. In my device, since side play is reduced to a minimum, a novice may operate the reamer, in the proper manner, for the pilot stem holds the tool tightly in place and the lower cutter compels and maintains proper alinement.

Figure 4 shows a modification of my improved reamer in which the pilot stem is shown as being removable from the shaft, thus enabling it to be readily replaced if worn or broken. Figure 5 shows the shank of the shaft provided with a tapering shoulder instead of the shoulder designated as 9 in Figure 4, the purpose of the tapered shoulder being to permit self-alinement of the cutters mounted upon the shank.

In Figure 2, it may be seen that it is impossible to make a pocket with my device that will shut off the flow of air to and from the port 24 and further the seat 22 will be the same size in every port reamed for the seat is the same size irrespective of how deep it is reamed. Angles 21 and 23 maintain the seat 22 at its proper size and in its relative position.

In operation a sufficient number of shims are placed between the cutters of my reamer to allow the cutter 11 to cut a seat of the desired size. The cutters and shims are placed on the shank of the tool and the nut 13 screwed home to firmly hold the cutters and shims between the nut and the shoulder 9. The plug 18 is then screwed into the hollow stem until the desired distension of the latter takes place. The tool is then pushed into the valve stem guide and the reamer rotated either with a wrench or a handle inserted in the hole 14. The cutters ream in three places simultaneously to the desired amount. The tool is lifted out when the operation is complete. By means of my tool not only may an old seat be reamed, but the top of the block and the port are cut at the same operation.

In Figure 7, a modification of my invention is shown. The cutters 10, 11 and 12, the spacing members 15, and the nut 13 are all mounted on a sleeve 26 which has a flare 27 at the upper end. In practice, the sleeve with the members mounted thereon is placed on a shaft, either a tapering one as shown in Figure 5 or one having an abutment shoulder as at 9, and held thereon by friction, by a nut screwed on the shaft, or any other suitable means.

Having thus described my invention what I claim and desire to secure by Letters Patent is:—

1. In a reamer, a shaft, a valve seat cutter mounted thereon, a pilot cutter also mounted on the shaft and adapted to cut prior to the reaming by the valve seat cutter to direct the first-mentioned cutter and to keep same

in alignment while the reamer is in operation, and means at the lower portion of the shaft below the cutters to hold the reamer vertical while reaming.

5 2. In a reamer, a shaft, cutters on the shaft for reaming a valve seat and portions of the wall on either side thereof, in one operation, the relations of the cutters being

such that the outer cutters determine the cutting width of the valve seat cutter, and 10 means for separating the cutters to vary said cutting width.

In testimony whereof, I hereunto affix my signature.

MAXIMILIAN W. THAETE.
